CLAIM

We claim the ornamental design for a display clip, as shown and described.

DESCRIPTION

FIG. 1 is a top front perspective view of the claimed design;

FIG. 2 is a bottom rear perspective view thereof;

FIG. 3 is a front view thereof;

FIG. 4 is a rear view thereof;

FIG. 5 is a left view thereof, the right view being a mirror image thereof;

FIG. 6 is a top view thereof; and,

FIG. 7 is a bottom view thereof.

The article is shown with a symbolic break in its length. The appearance of any portion of the article between the wavy break lines forms no part of the claimed design.
